Primary Examiner — Marianne Pandozzi*(74) Attorney, Agent, or Firm* — Cantor Colburn LLP(57) **CLAIM**

The ornamental design for a lid for water container, as shown and described.

DESCRIPTION

FIG. 1 is a perspective view of a lid for water container showing our new design;

FIG. 2 is another perspective view thereof;

FIG. 3 is a front view thereof;

FIG. 4 is a back view thereof;

FIG. 5 is a top plan view thereof;

FIG. 6 is a bottom plan view thereof;

FIG. 7 is a side view thereof; and,

FIG. 8 is another side view thereof.

The broken lines are for environmental purpose only and form no part of the claimed design.
